US00D799178S

(12) **United States Design Patent** (10) **Patent No.:** **US D799,178 S**
(45) **Date of Patent:** **** Oct. 10, 2017**

(54) **SHOE OUTSOLE**

(71) Applicant: **NIKE, Inc.**, Beaverton, OR (US)
(72) Inventor: **Georgina James**, Portland, OR (US)
(73) Assignee: **NIKE, Inc.**, Beaverton, OR (US)

(**) Term: **15 Years**

(21) Appl. No.: **29/574,233**

(22) Filed: **Aug. 12, 2016**

(51) **LOC (10) Cl.** **02-04**
(52) **U.S. Cl.**

USPC **D2/947**; D2/951

(57) **CLAIM**

The ornamental design for a shoe outsole, as shown and described.

DESCRIPTION

FIG. 1 is a front perspective view of a shoe outsole showing my new design;

FIG. 2 is a bottom view thereof;

FIG. 3 is a side view thereof;

FIG. 4 is an opposite side view thereof; and,

FIG. 5 is a rear perspective view thereof.

The broken lines showing the remainder of the shoe represent unclaimed subject matter and form no part of the claimed design.

1 Claim, 5 Drawing Sheets
